US00D581270S

(12) **United States Design Patent**
Gonzalez et al.

(10) **Patent No.:** **US D581,270 S**
(45) **Date of Patent:** **** Nov. 25, 2008**

(54) **ACTUATOR**

(75) Inventors: **Daniel Omar Gonzalez**, Buenos Aires (AR); **Diego Iglesias**, Ciudad De Buenos Aires (AR); **Javier Eduardo Mateu**, Buenos Aires (AR); **Martin Gabriel Urtubey**, Ciudad De Buenos Aires (AR)

(73) Assignee: **Conopco Inc.**, Englewood Cliffs, NJ (US)

(**) Term: **14 Years**

(21) Appl. No.: **29/286,408**

(22) Filed: **May 4, 2007**

(51) **LOC (8) Cl.** **09-07**

(52) **U.S. Cl.** **D9/448**

(58) **Field of Classification Search** ..... D9/754, D9/753, 752, 741, 728, 724, 697, 695, 529, D9/524, 516, 454, 447, 445, 444, 442, 443, D9/440, 439, 435, 434, 441, 686-693, 448, D9/438; D7/679, 590-597, 511, 510, 401.1, D7/398; 241/169, 169.1, 168; 229/906.1; 222/567, 566, 545, 482, 480, 356, 151, 149, 222/142.1-142.9, 635, 494, 491; 220/713, 220/254.1, 703, 269, 200, 234, 295, 304, 220/310.1, 378, 795, 804, 849, DIG. 19, 220/DIG. 4, DIG. 7, 915; D23/260, 259; 215/200, 231, 234, 364, DIG. 1; D24/216, D24/222, 224, 231; D19/57, 43; D28/7, D28/57

(57) **CLAIM**

The ornamental design for an actuator, as shown and described.

DESCRIPTION

FIG. 1 is a perspective view from the front, above and one side of an actuator;

FIG. 2 is a rear elevational view of an actuator;

FIG. 3 is an elevational view of the other side of an actuator;

FIG. 4 is a top plan view of an actuator; and,

FIG. 5 is an underneath plan view of an actuator.

The broken lines in FIGS. 1, 2, 3 and 5 showing a container define environmental subject matter only and form no part of the claimed design.
